SALAD TONGS

Emil S. Polk, Scarsdale, N.Y.

Application December 19, 1958, Serial No. 53,830

Term of patent 7 years

(Cl. D44—4)

Figure 1 is a front elevational view of salad tongs showing my new design.

Figure 2 is a rear elevational view.

Figure 3 is a right side elevational view of Figure 2; Figure 4 is a rear elevational view, parts displaced; and Figure 5 is a front elevational view, parts displaced.

I claim:

The ornamental design for salad tongs, substantially as shown.
